RIFLESCOPE ELEVATION ADJUSTMENT ASSEMBLY

Claus O. Huckenbeck, Sherman Oaks, Calif., assignor to
Bausch & Lomb Incorporated, Rochester, N.Y.

Filed Jan. 2, 1975, Ser. No. 538,086

Term of patent 14 years

Int. Cl. D16—06

U.S. Cl. D57—1 E

FIG. 1

FIG. 2

FIG. 3

FIG. 4

FIG. 5

FIG. 6

FIG. 1 is a front elevational view of a riflescope elevation adjustment assembly showing my new design;

FIG. 2 is a side elevational view thereof taken along the line 2—2 in FIG. 1;

FIG. 3 is a side elevational view thereof taken along the line 3—3 in FIG. 4;

FIG. 4 is a rear elevational view thereof taken along the line 4—4 in FIG. 2;

FIG. 5 is a top plan view thereof taken along the line 5—5 in FIG. 1; and

FIG. 6 is a perspective view thereof installed on a typical riflescope which is shown in broken lines for illustrative purposes only.

I claim:

The ornamental design for a riflescope elevation adjustment assembly, substantially as shown and described.
